UNITED STATES PATENT OFFICE

2,342,043

TRAY EQUIPPED CHAIR

Abraham G. Feldman, Chicago, Ill., assignor to
Storkline Furniture Corporation, Chicago, Ill.,
a corporation of Illinois

Application December 26, 1942, Serial No. 470,160

12 Claims. (Cl. 155—127)

My invention relates to tray equipped chairs; e. g., high chairs; and is particularly concerned with the provision of novel, simple and generally improved devices for detachably securing the trays to the arms of the chairs.

Among the important objects of the invention are:

The provision of a chair and tray so correlated and cooperating that the tray may be manipulated into attachment with the chair without the plane of the tray being inclined or tilted from the horizontal;

The provision of a chair and tray so correlated and cooperating that a quickly detachable connection between the tray and one of the chair arms is sufficient temporarily to support the tray horizontally on that arm alone;

The provision of a tray equipped chair which need comprise extremely little or no metal in its construction;

The provision of extremely simple, sturdy and effective devices for attaching the tray to the chair arms.

A salient feature of the present invention is a tray carried pivot-stud which may be manipulated into a horizontal channel, having one dead end, formed in one of the chair arms, to interengage the tray and arm against separation except by retrograde horizontal movement of the pivot-stud from such channel.

Another essential feature of the invention is an automatically engaging, manually releasable, spring pressed detent or plunger which is carried by the other chair arm and cooperates with a cam block or keeper to hold the tray against separation from the chair arms.

These and other features, objects and advantages of my invention will appear from the following detailed description, wherein reference is made to the accompanying two sheets of drawings in which:

Figure 1 is a view in perspective of a high chair embodying the present invention;

Figure 2 is a sectional view taken in the vertical plane of the line 2—2 of Figure 1 and looking in the direction indicated by the arrows;

Figure 3 is a top plan view, taken on the line 3—3 of Figure 2, which shows the pivot-stud engaging in the blind end of its cooperating chair arm channel;

Figure 4 is a view of the under side of the chair arm which carries the aforesaid spring pressed detent or plunger, this view being taken in the plane of the line 4—4 of Figure 2;

Figure 5 is a top plan view of the chair with

the tray, as depicted in full lines, supported horizontally on but one of the chair arms;

Figure 6 is a sectional view which may be regarded as taken in the medial fore-and-aft vertical plane of the chair when the tray is carried by and attached to both of the chair arms, as depicted in Figure 1;

Figure 7 is a detailed view, in top plan, of a chair arm, which illustrates how the channel with the one blind end and the undercut sides may have its open end at the inner edge, rather than the end edge, of the arm; and

Figure 8 is a fragmentary vertical sectional view which may be regarded as taken on the line 8—8 of Figure 7 and looking in the direction indicated by the arrows.

Similar characters of reference refer to similar parts throughout the several views.

In the drawings, 10 indicates the seat, 11 the leg structure, 12 the foot rest, 13 the back, 14 and 15 the arms, and 16—16 the arm supporting pins or spindles, of a high chair which, as thus far described, may be quite conventional. At 17 is a tray adapted to be manipulated into engagement with the arms 14 and 15 as hereinafter explained.

Referring first to Figures 2, 3, 5 and 6, it will be noted that a channel 18 is formed in the upper surface of arm 14. Such channel has an open end and a dead end. The open end of the channel, in this instance, lies at the forward end edge of the arm 14 and its dead end is laterally offset, as indicated at 19, toward the outer side edge of the arm. The walls of the channel are undercut or dove-tailed as indicated by full lines in Figure 2 and as indicated by dotted lines in Figures 3 and 5.

Carried on the under side of the tray 17, at one end thereof, is a pivot-stud 20. Such pivot-stud is preferably of frusto-conical shape and is adapted to enter, move lengthwise of, and interengage with the undercut walls of, the channel 18.

Carried on the underside of the tray 17, near the other end thereof, is a cam block or keeper 21. See Figures 2 and 5. Such cam block or keeper is provided with a rounded nose 22 for camming engagement with, and an aperture 23 for the reception of, the presently-to-be-mentioned spring pressed detent or plunger carried by the arm 15.

By referring to Figure 4, it will be noted that the under side of arm 15 is provided with a mortise or irregularly shaped recess 24, in which is disposed a leaf spring 25. Such leaf spring, which

is suitably formed of plastic material, has one end anchored between a block 26 and the contiguous portion of the mortise wall. The other or free end of the leaf spring engages in the notch 27 of a detent or plunger 28. Such detent or plunger, which reciprocates in a transverse bore intersecting the mortise 24, is provided with a finger piece 29 for use in retracting it against the pressure of the leaf spring 26. The tip 30 of the plunger 28 is conformed for reception by the bore 23 of the previously mentioned cam block or keeper 21.

If desired, a strap 31 may have one end attached to the bottom of tray 17, with the other end of the strap provided with a snap fastener grommet 32 adapted to cooperate in the usual manner with a snap fastener stud 33 carried on the front central portion of the under side of the seat 10. The purpose of the strap 31, of course, is to prevent a child from slipping out of the chair via the space between the tray and the chair bottom.

The tray 17, being readily detachable from the chair, may be brought to the chair laden with food. Then, by a simple manipulation which does not require that the plane of the tray be inclined or tipped from the horizontal, the frusto-conical pivot-stud 20 may be caused to enter the channel 18 and take a position at the blind end of the channel. Then, by swinging the horizontally disposed tray around the vertical pivot represented by the frusto-conical stud 20, the tip 30 of the plunger 28 will be brought into engagement with the rounded nose 22 of the cam block or keeper 21, will recede under the resultant camming action, and will then take a locking position in the aperture 23 of such cam block or keeper. Thus, the tray becomes firmly locked to and upon both of the chair arms.

Upon manually withdrawing the plunger 28 from engagement with the cam block or keeper 21, the tray readily may be manipulated out of engagement with the chair—again without there being any necessity for inclining or tipping the plane of the tray from the horizontal.

Figure 5 illustrates how the tray 17 may be very safely supported, in a horizontal plane, upon only the chair arm 14 when, for instance, it is desirable to place a child in the chair before swinging the tray to the position in which it is locked to both of the chair arms.

Figures 7 and 8 illustrate a slightly modified embodiment of my invention wherein the channel 18 has its open end at the inner side edge, rather than at the end edge, of the chair arm 14. In this instance, because the channel extends transversely of the arm 14, it is not necessary or desirable to have the blind end of the channel offset as is the case in the preferred and earlier described embodiment of my invention.

Having thus illustrated and described my invention, what I claim as new and desire to secure by Letters Patent of the United States is:

1. In combination with a chair and its arms, a tray, an upwardly opening channel presented by one of the arms, said channel having an open end and a dead end, a pivot-stud carried at one end of the tray, said pivot-stud adapted to enter the open end of such channel and move therein toward the dead end thereof, said channel and said pivot-stud being so conformed and related that the pivot-stud, after having entered such channel, cannot escape therefrom except by retrograde movement through its open end, and detent devices arranged to act between the other

arm and the other end of the tray and to prevent such pivot-stud from receding from the dead end of said channel.

2. In combination with a chair and its arms, a tray, an upwardly opening channel presented by one of the arms, said channel having an open end and a dead end, a pivot-stud carried at one end of the tray, said pivot-stud adapted to enter the open end of such channel and move therein toward the dead end thereof, said channel and said pivot-stud being so conformed and related that the pivot-stud, after having entered such channel, cannot escape therefrom except by retrograde movement through its open end, and detent devices arranged to act between the other arm and the other end of the tray and to prevent such pivot-stud from receding from the dead end of said channel, said detent devices comprising a keeper and a spring-urged plunger, one carried by the arm and the other by the tray, said plunger being adapted to engage said keeper when the tray is swung upon the axis represented by said pivot-stud to the position where said tray rests upon both of the arms.

3. In combination with a chair and the arms thereof, a tray which, while being held in a horizontal plane, may be manipulated into and out of engagement with the chair arms, a channel at the top of one of the arms, said channel having an open end, a dead end, and under-cut sides, a pivot-stud, carried at one end of the tray bottom, adapted to enter and move in said channel and to engage beneath the under-cut sides of the channel, and detent devices arranged to act between the other arm and the other end of the tray and to prevent such pivot-stud from receding from the dead end of said channel.

4. In combination with a chair and its arms, a tray, an upwardly opening channel presented by one of the arms, said channel having an open end and a dead end, a pivot-stud carried at one end of the tray, said pivot-stud adapted to enter the open end of such channel and move therein toward the dead end thereof, said channel and said pivot-stud being so conformed and related that the pivot-stud, after having entered such channel, cannot escape therefrom except by retrograde movement through its open end, and detent devices arranged to act between the other arm and the other end of the tray and to prevent such pivot-stud from receding from the dead end of said channel, said detent devices comprising a keeper carried on the under side of the tray and a spring pressed plunger carried by the arm, said plunger being adapted to engage said keeper when the tray is swung around the axis represented by said pivot-stud to the position wherein the tray rests upon both of the arms.

5. In combination with a chair and its arms, a tray, a channel at the top of one of the arms, said channel having an open end, a dead end and under-cut sides, a frusto-conical pivot-stud carried at one end of the tray bottom adapted to enter and move in said channel and to engage beneath the under-cut sides of the channel, and detent devices arranged to act between the other arm and the other end of the tray to prevent such pivot-stud from receding from the dead end of said channel.

6. In combination with a chair and its arms, a tray, a channel cut in the top of one of the arms, said channel having an open end at the forward extremity of the arm, extending longitudinally of the arm, and having a dead end which is offset toward the outer side of the arm.

said channel having under-cut sides, a pivot-stud, carried at one end of the tray bottom, adapted to enter and move in said channel and to engage beneath the under-cut sides of the channel, and detent devices arranged to act between the other arm and the other end of the tray and to prevent such pivot-stud from receding from the dead end of said channel.

7. In combination with a chair and its arms, a tray, a channel cut in the top of one of the arms, said channel having an open end at the inner side of the arm, extending transversely of the arm, and having a dead end and under-cut sides, a pivot-stud, carried at one end of the tray bottom, adapted to enter and move in said channel and to engage beneath the under-cut sides of the channel, and detent devices arranged to act between the other arm and the other end of the tray and to prevent such pivot-stud from receding from the dead end of said channel.

8. In combination with a chair and its arms, a tray, an upwardly open channel formed in one of the arms, said channel having an open end and a dead end, said channel extending longitudinally of the arm and having its dead end offset toward the outer side of the arm, a pivot-stud carried at one end of the tray, said pivot-stud adapted to enter the open end of said channel and move therein toward the dead end thereof, said channel and said pivot-stud being so conformed and related that the pivot-stud, after having entered said channel, cannot escape therefrom except by retrograde movement through its open end, and detent devices arranged to act between the other arm and the other end of the tray and to prevent said pivot-stud from receding from the dead end of said channel.

9. In combination with a chair and its arms, a tray, an upwardly open channel formed in one of the arms, said channel having an open end and a dead end, said channel extending longitudinally of the arm and having its dead end offset toward the outer side of the arm, a pivot-stud carried at one end of the tray, said pivot-stud adapted to enter the open end of said channel and move therein toward the dead end thereof, said channel and said pivot-stud being so conformed and related that the pivot-stud, after having entered said channel, cannot escape therefrom except by retrograde movement through its open end, and detent devices arranged to act between the other arm and the other end of the tray and to prevent said pivot-stud from receding from the dead end of said channel, said detent devices comprising a keeper and a spring-urged plunger, one carried by the arm and the other by the tray, said plunger being adapted to engage said keeper when the tray is swung around the axis represented by said pivot-stud to the position wherein the tray rests upon both of the arms.

when the tray is swung around the axis represented by said pivot-stud to the position wherein the tray rests upon both of the arms.

10. In combination with a chair and its arms, 5 a tray, a channel cut in the top of one of the arms, said channel having an open end at the inner side of the arm, said channel extending transversely of the arm and having a dead end, a pivot-stud carried at one end of the tray, said pivot-stud adapted to enter the open end of said channel and move therein toward the dead end thereof, said channel and said pivot-stud being so conformed and related that the pivot-stud, after having entered said channel, cannot escape therefrom except by retrograde movement through its open end, and detent devices arranged to act between the other arm and the other end of the tray and to prevent said pivot-stud from receding from the dead end of said channel.

11. In combination with a chair and its arms, 10 a tray, a channel cut in the top of one of the arms, said channel having an open end at the inner side of the arm, said channel extending transversely of the arm and having a dead end, 15 a pivot-stud carried at one end of the tray, said pivot-stud adapted to enter the open end of said channel and move therein toward the dead end thereof, said channel and said pivot-stud being so conformed and related that the pivot-stud, after having entered said channel, cannot escape therefrom except by retrograde movement through its open end, and detent devices arranged to act between the other arm and the other end of the tray and to prevent said pivot-stud from receding from the dead end of said channel.

12. In combination with a chair and its arms, 20 a tray, a channel presented by one of the arms, said channel having an open end and a dead end, a pivot-stud carried at one end of the tray, said pivot-stud adapted to enter the open end of such channel and move therein toward the dead end thereof, said channel and said pivot-stud being so conformed and related that the pivot-stud, after having entered such channel, cannot escape therefrom except by retrograde movement through its open end, and detent devices arranged to act between the other arm and the other end of the tray and to prevent such pivot-stud from receding from the dead end of said channel.

ABRAHAM G. FELDMAN.
